UNITED STATES PATENT OFFICE.

EGBERT A. REYNOLDS, OF WEEHAWKEN, NEW JERSEY, ASSIGNOR, BY MESNE ASSIGNMENTS, TO AUDIPHONE COMPANY OF AMERICA, OF NEW YORK, N. Y., A CORPORATION OF DELAWARE.

INTERCOMMUNICATING TELEPHONE SYSTEM.

Application filed July 16, 1920. Serial No. 396,795.

This invention relates to intercommunicating telephone systems.

An object of this invention is to provide intercommunicating telephone systems arranged for improved amplified transmission of the communicated sounds between the master station and any desired local station. A further object of the invention is to provide independence of circuit connection between the master station and the respective local stations and for connection of the master station with the desired local station while excluding the remaining local stations. A further object is to provide a circuit arrangement comprising two induction coils, connected in separately in the respective in-coming and out-going communication circuits and preferably in full metallic lines.

A further object of the invention is to provide means operable from any local station for setting an indicator or the like at the master station to indicate the local station calling, also to provide means for maintaining such indication during the communication and to automatically release such indication upon termination of communication with such local station, preferably under control of the master operator.

In accordance with the invention, in the preferred forms thereof, the master station is provided with a suitable indicator, means provided at the respective local station for setting the indication corresponding to such local station, key-setting means provided at the master station for closing the circuit between the master station and the local station and excluding the circuits of the other stations and means provided for releasing such indication upon hanging up the receiver at the master station.

In such preferred forms of the invention, in the event of two or more local stations sending in their respective indications, the indications of all such stations are retained in visible position during the successive periods of communication with the several local stations, until the master receiver at the master station is placed on its hook.

Further features and objects of the inven-

tion will be more fully understood from the following description and the accompanying drawings, in which—

Fig. 1 is a diagram of a simple form of system comprising the master station and a single local station and embodying my invention;

Fig. 2 is a more elaborate form of system embodying my invention and comprising the master station and four local stations;

Fig. 3 is a diagrammatic view of a master station and three local stations, embodying my invention;

Fig. 4 is a detail side elevation of a switch and control mechanism forming part of the arrangement shown in the aforesaid figures; and

Fig. 5 is a detail view corresponding to Fig. 4 showing the operated parts of the same in circuit closing position.

Referring to the form of the system shown in Fig. 1, the master station is indicated at 1 and comprises the master transmitter 2 and the master receiver 3. The single station is indicated at 4 and comprises the local transmitter 5 and the local receiver 6. In the form of the invention as shown, the circuit is fully metallic, that is to say, the conduction of the voice currents transmitted to and from the respective stations are transmitted over solely metallic conductors, and amplified by induction coils. The leads 7, 8 of the master transmitter 2 are connected at the plug-in points 9, 10, to the line conductor 11 and the lead 12. The conductor 11 is connected at 13 to one terminal of the primary coil 14 of the induction coil 15, the other terminal 16 being connected by the conductor 17 to the line conductor 18 connecting at 19 to the lead 19^a with the plug-in point 20 with the lead 21 connected to one terminal of the local transmitter 5. The other terminal of the local transmitter 5 is connected to the lead 22 and at the plug-in point 23 to the line conductor 24 connecting to one terminal 25 of the primary coil 26 of the induction coil 27, the other terminal 28 of the primary coil 26 being connected by the lead 29 at 30 to the aforesaid lead 12. The leads 31, 32 of the master receiver 3

100

- are connected at the respective plug-in points 33, 34 to the leads 35, 36 connected respectively to the opposite ends of the secondary coil 37 of the induction coil 27. The leads 38, 39 of the local receiver 6 are respectively connected at the plug-in points 40, 41 to the line conductors 42, 43 connected to the opposite terminals of the secondary coil 44 of the induction coil 15.
- 10 The source of electrical energy is shown in the form of the group of batteries 45, the negative terminal 46 of which is connected by the line conductor 47 at 19 to the lead 19^a extending to the plug-in point 20. The positive terminal 50 of the battery 45 is connected by the lead 51 to the plug-in point 52, at the master station, to the lead 53 connecting with the contact 54, associated with the contact 55, for purposes more fully described hereinafter. The contact 55 is connected by the lead 56 at the plug-in point 57 to the lead 58 connected at 30 to the lead 12, whereby upon removal by the master operator of the master receiver 3 from its hook, the contacts 54, 55, are brought into closed engagement and the circuit of the master transmitter 2 is connected through the battery 45 with the local receiver 6 through the energization of the primary coil 14 inducing amplified energization of its secondary coil 44, as set forth hereinabove. Similarly, the closure of the contacts 54, 55, effects the closing of the metallic circuit between the master receiver 3 and the local transmitter 5 through the primary coil 26, thence inductively under amplification through the secondary coil 37 of the induction coil 27.
- 15 It will thus be seen that the master transmitter when in operative position, is in metallic connection with its primary coil of one induction coil, whose secondary is in metallic connection with the receiver of the local station; also, that the local transmitter 45 is in metallic connection with the primary coil of a second and independent induction coil and that the master receiver is in metallic connection with the secondary of such second induction coil.
- 20 For the purpose of effecting signaling by the local operator to the master station, I have provided the buzzer 60 connected on one side by the lead 61 to the positive terminal 50 of the battery 45, and connected on the other side to the line conductor 62, connected at 63 to the line conductor 43, thence connected at 64 to the lead 65, running to the contact 66 of the push button 67, the other contact 68 of the push button 67 being connected by the lead 69 at 70 to the lead 21, connected through the lead 19^a to the line conductor 47 connected to the negative terminal 46. Such circuit relation affords direct closure of the signalling system 25 through the battery.

Thus in the operation of the aforesaid local station form of my invention, upon the local operator closing the push button 67 to audibly indicate through the buzzer 60 that communication is desired, with the master operator, the master operator upon removing his receiver 3 from its hook, closes the contacts 54, 55, and thus connecting the metallic line circuits between the master transmitter 2 and the local receiver 6, and the metallic line circuits between the local transmitter 5 and the master receiver 3, through the battery 45, each metallic circuit being independent of the other.

In Fig. 2, I have represented the type of my invention embodying the master station 80 comprising the master transmitter 81 and a master receiver 82, and four local stations indicated respectively by the brackets 83, 84, 85, 86. The plug-in points 87, 88 and 89, 90 of the master station correspond to the plug-in point of the master station shown in Fig. 1. The lead 91 from the plug-in point 88 connects with the lead 92 connecting with the plug-in point 93, at the master station, and thence with the lead 94 and contact 95. The contact 96 connecting with the contact 95 is connected by the lead 97 through the plug-in points 98 to the conductor 99 leading to the positive terminal 100 of the battery 101.

The set of contacts 95, 96 correspond to the set of contacts 54, 55, aforesaid, and are arranged to be in open position when the master receiver 82 is out of use, i. e., suspended on its usual hook, and to be placed in closed position when the master receiver 82 is removed from its hook.

The several local stations are each provided with a similar set of plug-in points, each set comprising four in number. These plug-in points are designated by like reference numbers, to wit, 102, 103, 104, 105, corresponding to the aforesaid plug-in points 40, 41, 23 and 20 for connection with the respective leads 38, 39, of each local receiver 6, and the leads 21, 22, of each local transmitter 5. Each local station is similarly provided with the push button 67 comprising the contacts 66, 68, as aforesaid, and connected by the leads 65, 69 to the respective local leads 39 and 21, respectively.

In view of the local telephone set at the other local stations 84, 85, 86 being similar to that shown at local station 83, the parts thereof have been omitted and are deemed not to require specific description.

The induction coils 110 and 111 are located at the master station, the terminals of the primary coil 112 of the induction coil 110 being respectively connected by the lead 113 to the plug-in point 87 and by the lead 114 to the negative terminal 115 of the battery 101. One terminal of the secondary coil 116 of the induction coil 110 is connected to the line conductor 117, connected at 118 to

the common line 119, connecting together the respective local plug-in points 103 of the several local stations.

The other terminal of the secondary coil 116 of induction coil 110 is connected by the lead 120 to the common conductor 121 indicated as a "strap" interconnecting the contacts 122, each of the sets of contacts 123 corresponding in number to the number 10 of local stations. The other contact 124 of each set of contacts 123 is arranged to be closed by its key 125. Each key 125 is positioned preferably at the master station; upon operation of the buzzer or the like by 15 any local operator, the master operator depresses the key 125 corresponding to such local station, and thereby connects such local station with the master station, and excluding all other local stations.

20 Each contact 124 of such set 123 of contacts is connected to the line conductor 126 to the plug-in point 102 at its local station.

The buzzer 140, located at the master station, is connected on one side through the line conductor 106 to each plug-in point 103 of the respective local stations and thus to each lead 39 and contact 66 of each local push-button 67 and is connected on the other side through the lead 107 to the positive terminal 100 of the battery 101. The remainder of the circuit of the buzzer is completed through the negative terminal 115 of the battery 101, through the conductor 114, thence through the common connector 25 or "strap" 130 of the enunciator 131, thence through the lead 132 of one terminal of the enunciator-magnet 133, thence through its other terminal through the line conductor 134 to the plug-in terminal 105 and thence 40 to the remaining contact 68 of its push-button 67. Upon energization of the magnet 133 of the enunciator 131 corresponding to the local station, its indicator or drop 135 is placed in visible position as in the usual 45 visual enunciator, and retained by its magnet in such visible position after release of pressure at the push-button 67 by the local operator. Arranged correspondingly with such set 123 of contacts, and operated by the same key 125, I have arranged the set 136 50 of contacts corresponding to the respective local stations and comprising a contact 137 connected through the line conductor 138 to each plug-in point 105 and thus through each lead 122 to one terminal of the local 55 transmitter 5, the other contact 139 of such set 136 being connected through the common lead 140 or conducting strap, through the lead 141, the one terminal of the coil 142 60 of the induction coil 111, thence through the lead 143 and lead 91 to the plug-in point 88 of the master station and thus to the master transmitter 81, thence through the plug-in point 87 thence through the primary 112 65 of the induction coil 110, thence through the

conductor 114 leading to the negative terminal 115 of the battery 101, thence through the positive terminal 100 of battery 101, lead 99, contacts 96, 95, and thence through the lead 91 completing the circuit of the master 70 transmitter 81.

In such arrangement, two induction coils are employed, irrespective of the number of local stations, each local station when connected in having its local receiver in metallic 75 circuit with the master transmitter through one induction coil and its local transmitter in metallic circuit with the master receiver through the other induction coil, while all of the other local circuits remain out of 80 circuit.

In Fig. 3, I have indicated schematically such system, the master transmitter being shown at 81 and the master receiver at 82, the contacts 95, 96 being operated in the 85 usual manner by the stem 145. The two induction coils 110 and 111 are shown positioned within the casing 146 of the combined enunciator 147.

To the stem 145 is also attached the arm 150 to which is secured the downwardly extending toe 151, see Figs. 3, 4 and 5, cooperating with the intermittent contact maker 152, shown in the form of a toothed circular member and coacting with the spring toe 151 in the nature of a ratchet. Each tooth 153 95 is related to the contact 148 so that as any tooth 153 depresses the spring 154 of the contact 148 to its maximum extent, the contact button 155 of the contact 148 is in engagement with the contact button 156 of the contact 149.

The several local stations designated 83, 84, 85, etc. correspond to the similarly designated local stations indicated in Fig. 2, and each local station is equipped with its sensitive transmitter 5 and amplifying receiver 6, located within a common housing 160, provided at its front with the spaced, inclined strips 161 enabling the sound waves 110 to pass therethrough and concealing the transmitter 5 and receiver 6. The push button 67 is conveniently positioned in the top of each housing 160, as indicated. The respective cables 162 include the line conductors of the communication and signalling systems referred to specifically hereinabove. 115

Assuming the master operator desires to call any station, say No. 1, to wit, the station indicated in Fig. 2 by reference No. 120 83, the key 125, see Fig. 3, corresponding to such station, is depressed thereby closing switches 123 and 136 respectively corresponding to such station and thus closing the circuit connecting the secondary 116 of the induction coil 110 with the receiver 6 of such local station and the primary of the induction coil 111 with the local transmitter 5 of such station. Upon the master operator removing his master receiver 82 125 130

from its hook 157, the hook 157 under action of its retractile spring 158 raises the stem 145 and causes the contact 96 to close with the contact 95, thereby connecting in the 5 master transmitter 2 with the primary 14 of the induction coil 15 and the master receiver 3 with the secondary 37 of the induction coil 27. Each of the incoming and outgoing circuits thus described are connected 10 in with the battery 101, through the circuits traced in detail hereinabove. To call any person at such local station, the master operator calls through his transmitter 2 "hello" with the name of the party desired, 15 or for any party in general, and the response at the local station is effected by such person answering at a distance from the local transmitter housed in its casing 160. Upon 20 completion of the communication desired by the master operator with the local party, the master operator hangs his receiver 82 on its hook 157, causing the stem 145 to be depressed, whereby the spring arm 151 engages a tooth 153 causing an advanced tooth 153 25 in its rotation to engage the toe 154 of the contact 148 and thus closing the circuit between the contacts 148, 149, through the line 157 see Fig. 2 connecting at 157^a with the line 158 leading to one side of the reset or 30 restoring magnet 159 and connected on the other side through the lead 159^a to the lead 114 connecting with the negative terminal 115 of the battery 101, the positive side 100 of the battery 101 being connected therough 35 35 the conductor 99 and lead 97 with the contact 149. The reset magnet 159 is provided with a suitable armature 160 arranged in any approved manner relative to the keys 125 to reset the keys 125 to normal position. 40 Such closure of the contacts 148, 149 also closes the circuit through the battery and the restore magnets 161 of the enunciator to cause the "drop" 135 to be returned to neutral, in which circuit connection the contact 148 is connected through the lead 157 at the point 157^a to the lead 162 to the strap 163 connected through the conductor 164 to one end of the restore magnet 161, the other end of the restore magnet 161 being connected through the conductor 165 to the 45 strap 130 connected through the lead 114 to the negative terminal 115 of the battery 101, the positive terminal being connected to the lead 99 to the lead 97 connected to the other contact 149.

60 Preferably, each local receiver embodies the construction set forth and claimed in the application entitled Sound reproducing instrument, Serial No. 183,215, filed July 28, 1917, filed by me jointly with De Elbert A. Reynolds, and each local transmitter preferably is of the construction set forth and claimed in the copending application Serial No. 240,418, entitled Audiphones, filed June 17, 1918, by De Elbert A. Reynolds.

In the aforesaid preferred arrangement it will appear that the two induction coils, located at the master station, are common for the respective local stations, and that upon connecting any desired local station, the remaining local stations are excluded from the circuit, also that the signalling circuit operating the enunciator at the master station embodies a conductor leading from each push button or equivalent, at the local station connected with the secondary circuit of one induction coil and the primary circuit of the other induction coil; also that upon the master operator placing his receiver on its hook, the intermittent current transmitted from the battery passes through a dual circuit connecting in parallel the restoring magnet of the enunciator and the restoring magnet of the keys, such intermittent energization being preferred for the purpose of causing all circuits to be in open position when the master receiver and its hook have attained its final or full nonoperative position.

Whereas I have described my invention by reference to specific forms thereof, it will be understood that many changes and modifications may be made without departing from the spirit of the invention as defined by the appended claims.

What I do claim and desire to have protected by Letters Patent is:—

1. The combination with a master transmitter and a master receiver, of a plurality of local stations, each local station comprising a local transmitter, a local receiver, a circuit for each local transmitter fully closed at all times through its local transmitter and a correlated circuit for each local receiver fully closed at all times through its local receiver, an induction coil connected in common with the local receiving circuits, a second induction coil connected in common with the local transmitter circuits, and means for connecting in at will the set of correlated local circuits of any desired local station with said master transmitter and said master receiver while maintaining out of circuit at all times the remaining sets of local circuits.

2. The combination with a master station comprising a master transmitter and a master receiver, of a plurality of local stations, each local station comprising a local transmitter and local receiver, a local circuit normally closed through its local transmitter, a correlated local circuit normally closed through its local receiver, a source of electrical energy, an induction coil, leads connecting the master transmitter with the primary of said induction coil, a second induction coil, means connecting the secondary of said second induction coil with said master receiver, means connecting at will the local circuit through the desired local receiver

1

with the secondary of said first induction coil, means for connecting at will the correlated local circuit of the desired local transmitter with the primary of said induction coil and manually operated means located at the respective local stations for signalling the master station, said signalling means and said two connecting means including common conductors.

10 3. The combination with a master station comprising a master transmitter and a master receiver, of a plurality of local stations, each local station comprising a local transmitter and local receiver, a local circuit normally closed through its local transmitter, a correlated local circuit normally closed through its local receiver, a source of electrical energy, an induction coil, leads connecting the master transmitter with the primary of said induction coil, a second induction coil, means connecting the secondary of said second induction coil with said master receiver, means connecting at will the local circuit through the desired local receiver with the secondary of said first induction coil; means for connecting at will the correlated local circuit of the desired local transmitter with the primary of said induction coil and manually operated means located at the respective local stations for signalling the master station, said signalling means including a conductor common with said first named connecting means and a conductor common with said second named connecting means.

35 4. The combination with a master station comprising a master transmitter and a master receiver, of a plurality of local stations each local station comprising a local transmitter and a local receiver, a local circuit normally closed through its local transmitter, a correlated local circuit normally closed through its local receiver, a source of electrical energy, selector circuit means for connecting the master station with the set of the aforesaid correlated circuits of any desired local station, announcing means located at the master station, operable means located at the respective local stations for operating said announcing means and means for automatically restoring said selector circuit means and said announcing means to neutral.

5. The combination with a master station comprising a master transmitter and a master receiver, of a plurality of local stations each local station comprising a local transmitter and a local receiver, a local circuit normally closed through its local transmitter, a correlated local circuit normally closed through its local receiver, a source of electrical energy, selector circuit means for connecting the master station with the set of the aforesaid correlated circuits of any desired local station, announcing means lo-

cated at the master station, operable means located at the respective local stations for operating said announcing means and means automatically operated upon effecting the master station to non-operative position for 70 restoring said selector circuit means and said announcing means to neutral.

6. The combination with a master station comprising a master transmitter and a master receiver, of a plurality of local stations each local station comprising a local transmitter and a local receiver, a local circuit normally closed through its local transmitter, a correlated local circuit normally closed through its local receiver, a source of electrical energy, selector circuit means for connecting the master station with the set of the aforesaid correlated circuits of any desired local station, announcing means located at the master station, operable means located at the respective local stations for operating said announcing means and means automatically operated upon effecting the master station to non-operative position for restoring said selector circuit means and said announcing means to neutral, said automatic restoring means comprising a circuit means respectively connecting said selector circuit means and said announcing means in parallel with one another with said source of electrical energy. 75 80 85 90 95

7. The combination with a master station comprising a master transmitter and a master receiver, of a plurality of local stations each local station comprising a local transmitter and a local receiver, a local circuit normally closed through its local transmitter, a correlated local circuit normally closed through its local receiver, a source of electrical energy, selector circuit means for connecting the master station with the set of the aforesaid correlated circuits of any desired local station, announcing means located at the master station, operable means located at the respective local stations for operating said announcing means and means automatically operated upon effecting the master station to non-operative position for restoring said selector circuit means and said announcing means to neutral, said automatic restoring means including a set of normally spaced contacts and means for moving said contacts to closed position operable upon effecting the master receiver to non-operative position. 100 105 110 115 120

ciator, restoring means for said enunciator, selector circuit means connecting the master station with any desired local station, said selector circuit means comprising a plurality of keys corresponding to the respective local stations, restoring means for said keys, and means operable upon placing said master

receiver on said hook for effecting intermittent connection between said source and said enunciator restoring means and said restoring means for said keys. 10

In testimony whereof I have signed this specification this 28th day of June, 1920.
EGBERT A. REYNOLDS.
